UNITED STATES PATENT OFFICE.

EDWARD E. HYLAND, OF CHICAGO, ILLINOIS.

TRANSFER-TICKET.

1,338,018.

Specification of Letters Patent. Patented Apr. 27, 1920.

Application filed April 20, 1916. Serial No. 92,401.

To all whom it may concern:

Be it known that I, EDWARD E. HYLAND, a citizen of the United States, and a resident of the city of Chicago, county of Cook, 5 and State of Illinois, have invented certain new and useful Improvements in Transfer-Tickets, of which the following is a specification.

My invention relates to improvements in 10 transfer tickets especially adapted for use on street railway lines, and has for its object the provision of an improved construction of this character which will greatly simplify the work of conductors on such 15 lines and will prevent unauthorized use of the transfers.

The invention consists in the combinations and arrangements of parts hereinafter described and claimed.

20 The invention will be best understood by reference to the accompanying drawings forming a part of this specification, and in which,

Figure 1 is a face view of one form of 25 ticket embodying my invention.

Fig. 2, a face view of a modified form of dial which may be used on the ticket.

Fig. 3, another form of dial which may be used on the ticket,

30 Fig. 4, another form of dial which may be used on the ticket, and

Fig. 5 a face view of a modified form of ticket also showing another form of dial.

The form of ticket 6 illustrated in Fig. 1 35 is marked at the top 7 with the day of the week and month and the street car line upon which it is to be used. At each side, the upper portion of the ticket is marked with the words "East" and "West" and

40 with marks indicating antemeridian and postmeridian time, the words East and West overlying said time marks, as indicated. Immediately below such markings is a statement as to the time in which the 45 transfer is good. The upper central portion of the ticket is provided with a central dial 8 having an outer annular band shaded and marked to indicate postmeridian time and printed with the hours from one to twelve

50 inclusive. Between said hour marks are arranged minute marks in steps of five from zero to fifty-five, so that the postmeridian time at which the transfer expires may be readily indicated thereon by punching an hour and a minute mark. Within this

postmeridian band is a comparatively narrow band upon which the name of the railway and an officer thereof may be marked, if desired. Within this marking band is another annular time band which is left 60 unshaded and marked for antemeridian time and with the hours from five to eleven inclusive, whereby an antemeridian time may be readily indicated by punching the proper hour in said antemeridian band and 65 the proper minutes in the postmeridian band. Shaded spaces 9, 10, 11 and 12 are marked respectively to indicate the stopping of a car at a depot or station, any special emergency, a half-fare and an extension trip, any one of which may be readily indicated by punching the corresponding space. The ticket is also given a suitable number below the time dial and marked with the year in which it is to be 70 used. A transfer check 13 is detachably connected with the body of the transfer ticket by means of a line of perforations and is suitably marked as to the manner in which it may be used, the number, the street 75 car line issuing the same, the date and the name of the company. A detachable refund check 14 is also provided and detachably arranged below the transfer check and connected thereto through a line of perforations which permits of ready detachment. This refund check is marked with the general number of the ticket, directions for 80 use, date, name of the company, and name of an officer of the company, as indicated. 85

In use, when the transfer is issued by a conductor, the direction of travel of the issuing line and the time at which the transfer expires are punched in the dial thereof, as will be readily understood. If desired, the 90 direction of travel and a general indication as to antemeridian or postmeridian time of expiration may also be punched at the top of the ticket, thus tending to avoid mistakes and arguments with passengers. A transfer 95 ticket thus issued is presented on the next line, and, if correctly used, the direction of the next line is also punched on the dial thereof for guidance on future lines. Thus, it will be seen, the transfer may be readily used for all legitimate purposes but illegitimate use thereof is positively prevented. The refund check may, or may not, be used as desired. When used, an additional price is paid for the original fare and a refund 100 105 110

given upon proper re-use of the transfer. The refund check may be also made available as a ticket for a general ride at any time, as indicated.

5 The form of dial 15, illustrated in Fig. 2, is provided with an outer annular band 16 shaded and marked to indicate postmeridian time and an inner segmental section of an annular band 17 unshaded and 10 marked to indicate antemeridian time. The outer annular band 16 is marked with the hour numbers from one to twelve inclusive, the numbers from five to eleven inclusive being extended into the antemeridian section 15 so as to permit of punching of said hours either in the postmeridian band or the antemeridian band, thus making provision for indicating any desirable hour of use. The minutes are indicated as before. The 20 unused section of the antemeridian band may be utilized for indicating the time of expiration of the transfer, as shown.

The form of dial illustrated in Fig. 3 is especially adapted for use on day cars, 25 namely cars which start running at five in the morning and cease running at five in the evening. On this dial the outer annular band is divided into segmental sections 19 and 20, the section 19 being shaded and 30 marked to indicate postmeridian time and containing hour marks twelve, one, two, three, four and five, as indicated. The unshaded section 20 is marked to indicate antemeridian time and with the hours five to 35 eleven inclusive, as indicated. Minute marks, in the steps of ten, are arranged between the hour marks in both the post and antemeridian sections, and the central portion of the dial utilized for giving general 40 information, as shown.

The form of dial 21, as shown in Fig. 4, is especially adapted for use on night cars, namely cars which start running at five o'clock in the evening and run until five the 45 next morning. This dial is identical with the one illustrated in Fig. 3, except that the ante and the postmeridian indications are reversed.

The form of ticket, illustrated in Fig. 5, 50 is marked at the top 24 to indicate the car lines upon which it may be used and with shading and marking to indicate antemeridian and postmeridian time and direction of travel. The upper central portion of 55 the ticket is marked to indicate the day of the week and month, and also to indicate directions of travel, ante and postmeridian time and the line issuing the same. The lower central portion of the ticket is provided with 60 a dial 25 which is arranged to always indicate postmeridian time unless otherwise punched, as most of the travel upon street railway lines is during postmeridian hours. The minute marking is also somewhat dif- 65 ferent, provision being made for indicating

the minutes after each individual hour. At the edges, spaces are also marked for month indications, as shown.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A transfer ticket having a dial thereon marked to indicate both ante and postmeridian hours and also directions of travel, substantially as described.

2. A transfer ticket having a dial thereon marked around its outer portions to indicate both ante and postmeridian hours and also in its central portions with directions of travel, substantially as described.

3. A transfer ticket having a detachable transfer coupon attached thereto, said ticket having a dial thereon marked to indicate both ante and postmeridian hours, substantially as described.

4. A transfer ticket marked at its top with the day of the week and month, the car line upon which it is to be used, the direction of use and ante and postmeridian time, the central portion of said ticket being provided with a dial having an outer annular band marked to indicate postmeridian time and the hours from one to twelve and between said hour marks with minute marks from zero to fifty-five, said dial being provided with an inner annular band marked to indicate antemeridian time and with the hours from five to eleven, the central portion of said dial being marked with the day of the month and the four directions of the compass, said central portion of said ticket being also marked to indicate an emergency, an extension, a half-fare and the stopping of the car at a depot or station, substantially as described.

5. A transfer ticket marked at its top with the day of the week and month, the car line upon which it is to be used, the direction of use and ante and postmeridian time, the central portion of said ticket being provided with a dial having an outer annular band marked to indicate postmeridian time and the hours from one to twelve and between said hour marks with minute marks from zero to fifty-five, said dial being provided with an inner annular band marked to indicate antemeridian time and with the hours from five to eleven, the central portion of said dial being marked with the day of the month and the four directions of the compass, said central portion of said ticket being also marked to indicate an emergency, an extension, a half-fare and the stopping of the car at a depot or station, substantially as described.

compass, said central portion of said ticket being also marked to indicate an emergency, an extension, a half-fare and the stopping of the car at a depot or station; and a detachable transfer coupon and a refund check attached to said ticket, substantially as described.

In testimony whereof I have signed my name to this specification in the presence of two subscribing witnesses.

EDWARD E. HYLAND.
